UNITED STATES PATENT OFFICE.

C. GEORGE SPENGLER, OF HOBOKEN, NEW JERSEY, ASSIGNOR, BY DIRECT AND MESNE ASSIGNMENTS, TO CORNELIUS KIEL AND ROSALIE CHRISTIANE SPENGLER, BOTH OF SAME PLACE.

SYRINGE.

SPECIFICATION forming part of Letters Patent No. 359,642, dated March 22, 1887.

Application filed December 15, 1886. Serial No. 221,633. (Model.)

To all whom it may concern:

Be it known that I, CHRISTIAN GEORGE SPENGLER, a resident of Hoboken, in the county of Hudson and State of New Jersey, 5 have invented an Improvement in Syringes, of which the following is a full, clear, and exact description, reference being made to the accompanying drawings.

My invention relates to syringes, and has 10 for its object to provide a syringe which will give a continuous stream of liquid, as will be more fully hereinafter set forth.

In the accompanying drawings, Figure 1 is 15 a view of my improved syringe, partly in section. Fig. 2 is a sectional view on the line *c c*, Fig. 1. Fig. 3 is a sectional view on the line *k k*, Fig. 1. Fig. 4 is a sectional view on the line *k' k'*, Fig. 1.

A is the compression-bulb, which is 20 provided with the usual suction-pipe, B. To the end of the bulb opposite that to which the suction-pipe B is attached is secured the cap D, having the tip *a* and the passage *b* therein. Over the tip *a* is secured one end of the inner 25 tube, E, and surrounding said inner tube, E, is an outer tube, F, of larger diameter than the tube E, so as to provide an annular chamber, E', between the walls of said inner and outer tubes.

One end of the outer tube, F, is drawn over 30 the cap D and securely fastened thereto, so as to close the end of said annular chamber E'. The other end of the inner tube, E, embraces a projection, *d*, on the inner end of the cap G, 35 said projection being bored out, so as to form a passage, *e*, therein, which passage has a lateral opening, *f*. (See Figs. 1 and 3.) That portion of the inner tube, E, which embraces the projection *d* is cut away opposite the opening *f*, so as to allow the passage of the liquid 40 through it. The outer tube, F, also embraces at its opposite end the cap G, thus forming an inclosed annular chamber, E', between the cap D and the cap G. The cap G is provided with 45 the passages *g*, which lead from the annular chamber E', between the inner and outer tubes, into the chamber *h* of the cap G. Said cap G is provided with the usual tip or nozzle, H, of suitable material. The area of the passage *i*

in the nozzle H is smaller than the area of the 50 opening *e*, for the purpose which will more fully hereinafter appear.

When the liquid has been drawn by suction into the bulb A, by compressing the latter the liquid is forced through the inner tube, E, 55 and out at the opening *f* into the annular chamber E', heretofore described, and thence finds its way through the passages *g* to the nozzle H. As the amount of liquid which is supplied by the compression of the bulb A is 60 greater than that which can pass through the passage *i* of the nozzle H during the compression of the bulb, the annular chamber E' will be partly filled with liquid, and at the same time the air is compressed in said chamber to 65 a greater or less extent, which air, during the subsequent suction operation of the bulb supplies the necessary power to continue the stream.

My improved syringe also possesses the advantage that the annular chamber E' can be charged with a quantity of liquid under more or less pressure, and being thus provided with a storage-reservoir, the apparatus can be carried around while in this condition, so as to 70 be ready for immediate use without the necessity of having a vessel at hand containing the liquid to be injected. All that is necessary in order to use the syringe while in this condition is to compress the bulb A, when the 75 liquid will immediately be forced out by the compression of the air in the annular chamber.

This improved form of syringe is simple in construction, not liable to get out of order, and requires no special form of tube for its 80 construction, as has heretofore been the case.

I do not wish to limit myself to the exact details herein shown and described, as they 85 may be varied without departing from the spirit of my invention.

Having now described my invention, what I claim is—

1. In a syringe, the combination of an inner tube with an outer tube communicating therewith, for the purpose of allowing the liquid to 90 flow from one of said tubes directly into the other, as and for the purpose set forth.

2. The combination of an inner tube and an

outer tube with a compression-bulb and a tip or nozzle, H, said inner tube communicating with the compression-bulb and the annular chamber formed between the inner and outer tubes, and the outer tube communicating with the nozzle, substantially as described.

3. The combination of the cap G, having the opening g and projection d, which projection has a perforated recess, e, therein, with an inner tube, E, fitting over said projection and having an opening registering with the recess e, and an outer tube, F, closed at one end and fitting over the cap G at the other, and means for supplying said inner tube with liquid under pressure, substantially as described.

4. The combination of an outer tube, F, closed at one end and connected to a nozzle at its other end, and an inner tube, E, of smaller diameter, said inner tube being connected at one end with means for supplying liquid un-

der pressure and closed at the other end and having an opening into the chamber formed between the inner and outer tubes, with a nozzle which has a smaller orifice or passage than the said opening in the inner tube, substantially as described.

5. The combination of the bulb A, cap D, having projection a and passage b therein, outer tube, F, fitting over said cap D, and inner tube, E, fitting over said projection a, with the cap G, having nozzle H, openings g, and projection d, which projection has the passage e therein, said inner tube fitting over said projection d and having an opening registering with the passage e, and the outer tube, F, fitting over the cap D, substantially as described.

C. GEORGE SPENGLER.
